CLAIM

The ornamental design for an incubator, as shown and described.

DESCRIPTION

FIG. 1 is a top, rear, left side perspective view of an incubator showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded view thereof.

The evenly dashed broken lines in FIGS. 2,3,4,5,6, and 8 illustrate the features of the incubator and form no part of the claimed design.

1 Claim, 9 Drawing Sheets
